UNITED STATES PATENT OFFICE

135,362

DESIGN FOR AN INTERIOR PARTITION STRUCTURE

Raymond Jackson Myers, Detroit, Mich.

Application December 14, 1942, Serial No. 109,034

Term of patent 3½ years

To all whom it may concern:

Be it known that I, Raymond Jackson Myers, a citizen of the United States, residing at Detroit, in the county of Wayne and State of Michigan, have invented a new, original, and ornamental Design for an Interior Partition Structure, of which the following is a specification, reference being had to the accompanying drawing, forming part thereof.

In the drawing:

Fig. 1 is a perspective view of an interior partition structure embodying my new design.

Fig. 2 is an enlarged perspective view of a fragment of the partition structure shown in Fig. 1.

I claim:

The ornamental design for an interior partition structure, as shown.

RAYMOND JACKSON MYERS.
